UNITED STATES PATENT OFFICE.

WILLIAM DENNISON TABER, OF CRANSTON, RHODE ISLAND, ASSIGNOR TO
CARRIE E. KNIGHT AND RHOBAY KNIGHT, OF SAME PLACE.

WALL-PAPER TRIMMING, PASTING, AND MATCHING MACHINE.

SPECIFICATION forming part of Letters Patent No. 657,466, dated September 4, 1900.

Application filed April 11, 1900. Serial No. 12,443. (No model.)

To all whom it may concern:

Be it known that I, WILLIAM DENNISON TABER, a citizen of the United States, and a resident of Cranston, in the county of Providence and State of Rhode Island, have invented a new and Improved Wall-Paper Trimming, Pasting, and Matching Machine, of which the following is a full, clear, and exact description.

10 The object of the invention is to provide a new and improved wall-paper trimming, pasting, and matching machine which is simple and durable in construction and arranged to accurately cut the selvage of the paper, to apply paste to the back of the paper, and to match the paper according to the pattern in lengths corresponding to the height of the walls on which the paper is to be applied.

15 The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a perspective view of the improvement. Fig. 2 is a longitudinal sectional elevation of the same on the line 2 2 in Fig. 3. Fig. 3 is an end elevation of the same. Fig. 4 is a transverse section of part of the improvement, and Fig. 5 is a perspective view of the paste-table.

30 The improved machine is mounted on a suitable framework essentially consisting of standards A A', connected with each other by side rails B B', as is plainly shown in the drawings, the standards having folding legs A².

35 On the back of the standard A is formed a transversely-extending guideway A³, in which is mounted to slide transversely a rack C, having arms or brackets C' with slots for receiving a rod E for carrying a roll of paper

40 F, the latter resting at one end against a flange E' on said rod, as is plainly shown in the drawings. A spring E² presses against the rod, so as to hold the same in proper position in its bearing on the brackets C'. The

45 rack C is held laterally adjustable by a screw D, as indicated in Fig. 4, so as to bring the selvage edge of the paper in proper relation to the knives or cutters, as hereinafter more fully described.

The paper unwinding from the roll of paper 50 F is passed under a guide-roller G and then upward over a second guide-roller G', from which the paper passes between the drawing-rollers H H', having rubber-covered peripheries for drawing the paper forward when the 55 rollers are turned, as hereinafter more fully explained. The top drawing-roller H has its shaft H² journaled in bearings H³, fitted to slide vertically in suitable guideways A⁴, forming part of the standards A, and said 60 bearings H³ are pressed on by springs H⁴ and are held vertically adjustable by screw-rods H⁵, as indicated in Fig. 4. The shaft H⁶ of the other drawing-roller H' is journaled in fixed bearings in the standards A. 70

The rollers H H' terminate at one end a suitable distance from the ends of their shafts H² H⁶, as indicated in Figs. 3 and 4, and on these ends of the rollers are secured circular knives or cutters I I' for trimming off the 75 selvage of the paper as the latter passes between the rollers H H'. A spring I², coiled on the shaft H², rests with one end on a bearing H³ and presses with the other end against the cutter or knife I, so as to hold the same in 80 firm shearing contact with the other cutter or knife I', and thereby insure a proper cutting of the selvage from the paper. In order to properly guide the paper to the drawing-rollers and to the knives I I', so that the 85 latter cut off the selvage at the proper place, it is necessary to adjust the rack C transversely by the screw D, as previously mentioned, to bring the paper F to the proper position. A scale D' serves to indicate the distance the rack is to be adjusted transversely 90 according to the width of the selvage to be cut off from the paper.

When it is desired to cut or slit a piece of wall-paper to any desired width, I make use 95 of a cutting-disk J, held adjustable by a set-screw J' on a shaft J², loosely journaled at one end in a suitable bearing J³, carried by

the standard A at one side of the machine, the other end of the shaft being adapted to engage one of two open bearings J⁴ J⁵ on the other standard A, the bearing J⁴ being located 5 in front and somewhat lower than the other bearing J⁵. When the shaft is in the bearing J⁴, it extends above and parallel to the roller G', and the cutting-disk J is adjusted lengthwise on the shaft J² to cut the paper to 10 a desired width as the paper passes over the roller G', which is preferably made of glass. When the disk J is not to be used for the purpose mentioned, then the operator lifts the end of the shaft J² out of the bearing J⁴ and 15 places it in the higher bearing J⁵, so that the disk J is moved out of contact with the paper passing over the roller G'. A spring J⁶ presses on the end of the shaft J² to hold the same in position in either bearing J⁴ or J⁵. 20 A graduated bar J⁷, carried by the standards A, permits of readily setting the disk J to indicate the width of the paper to be cut or slit.

The trimmed or slit paper after leaving the 25 drawing-rollers H H' passes over an upright table K, the printed or ornamented side of the paper being on the surface of the table and the back of the paper being in contact with a revoluble brush L, which serves to 30 apply paste to the back of the paper. The brush L receives its supply of paste from the peripheral surface of a fountain-roller N, the lower portion of which extends into the paste contained in a receptacle O, carried by the 35 standards A. The receptacle O has a hinged cover O', which extends over the top of the fountain-roller N and over the brush L and covers the same, the upper or free end of said hinged cover being locked in place by 40 locking-springs O². The trimmed paper, with the paste applied to the back thereof, after leaving the table K extends downward upon a traveling apron or belt P, passing over rollers P' P'', journaled in suitable bearings in the 45 standards A A'. The apron P thus carries the paper along, and by having the side rails B provided with a graduation B² the operator is enabled to readily match the paper by cutting the same in proper lengths, according to 50 the height of the walls on which the paper is to be applied.

The table K is preferably made in two parts K' K², adjustably held in a transverse direction, so as to allow of making the table 55 narrower or wider, according to the width of the paper under treatment, it being understood that the table is adjusted to a width somewhat less than the width of the trimmed paper, so that the edges of the paper bend 60 over the sides of the table when the paste is applied, and consequently the extreme side edges of the paper do not receive paste. The sections K' K² are preferably hung on a rod K³, carried by the standards A, and the lower 65 ends of said sections are engaged by a rod

K⁴, as shown in Fig. 5, a screw K⁷ or other suitable means being employed for adjusting the sections K' K² transversely for the purpose mentioned. In order to adjust the table K to bring the back of the paper in proper 70 contact with the paste-applying brush L, a screw-rod K⁶ is provided, screwing in a bearing A⁵ on the standards A and abutting against the inner face of the table, as shown in Fig. 2.

In order to impart the desired and necessary motion to the several parts above enumerated, I provide one end of the shaft H⁶ with a crank-arm Q, adapted to be taken hold of by the operator to turn the roller H', and as the other roller H is forced into frictional contact by the springs H⁴, with the paper passing between the rollers, it is evident that the roller H turns with the roller H' and feeds the paper forward. On the shaft H⁶, next to 85 the crank-arm Q, is secured a pulley R, connected by a crossed belt R' with a pulley R², secured on the shaft J². Thus when the shaft H⁶ is turned a rotary motion is given to the shaft J² and the disk J on the said rod for 90 slitting the paper, as before explained. On the shaft H⁶ is also secured a gear-wheel S, in mesh with a gear-wheel S', secured on the brush-shaft L, to rotate the latter when the drawing-rollers are rotated, it being understood 95 that the shaft of the brush L is journaled in the sides of the cover O', so that when the latter is swung open the gear-wheel S moves out of mesh with the gear-wheel S. Thus the paper may be fed forward without 100 applying paste to a portion thereof whenever desired, the operator then simply swinging the cover O' open. On the shaft H⁶, adjacent to the gear-wheel S, is secured a pulley S², over which passes a belt S³, also passing over 105 a pulley S⁴, secured on the shaft of the apron-roller P', so that when the drawing-rollers are turned a traveling motion is given to the apron P. On the inner face of the pulley S⁴ is arranged or formed another pulley S⁵, connected by a belt S⁶ with a pulley S⁷ on the fountain-roller N, so that the latter is rotated 110 in the casing O to carry a uniform amount of paste to the brush L.

From the foregoing it is evident that the 115 machine can be readily adjusted to accommodate wall-paper of any width and to allow of adjusting the paper so that the cutters or knives trim the same to the desired width. It will also be seen that after the paper is 120 trimmed the brush L applies the paste evenly on the back of the paper, and as the latter moves forward with the apron it can be readily matched and cut in desired lengths.

Having thus fully described my invention, I claim as new and desire to secure by Letters Patent—

1. A machine of the class described, comprising a pair of drawing-rollers for the paper to pass between, circular knives or cutters on 130

- said rollers, to trim the paper by cutting off the selvage, a spring for holding the knives in shearing contact, an upright table forward of said rollers and over which the paper passes, a brush in front of said table for applying paste to the paper, means for supplying paste to the brush, and means for adjusting the table relatively to the brush, as set forth.
- 5 2. A machine of the class described, comprising a pair of drawing-rollers for the paper to pass between, circular knives or cutters for trimming the paper at one side thereof, a table adjustable in width and over which the paper passes after leaving the rollers, a revolute brush in front of the table, for applying paste to the back of the paper, and means for adjusting the table relatively to the brush, as set forth.
- 10 3. A machine of the class described, comprising a pair of drawing-rollers for the paper to pass between, circular knives or cutters for trimming the paper at one side thereof, an upright table over which the paper passes after leaving the rollers, a revolute brush in front of the table for applying paste to the back of the paper, a receptacle for paste supported forward of the table and under which the paper passes from the table, a roller in
- 15 said receptacle for supplying paste to the brush, and a traveling apron upon which the paper passes after passing over the table, to move the trimmed and pasted paper forward, as set forth.
- 20 4. A machine of the class described, comprising a rack for supporting the roll of paper, guide-rollers for the paper after it unwinds from the said rack, a driven shaft carrying an adjustable cutting-disk, over one of the said rollers, and two bearings for one end of the shaft and located one below the other, substantially as shown and described.
- 25 5. A machine of the class described, comprising a pair of drawing-rollers for the paper to pass between, circular knives or cutters for trimming the paper at one side thereof, an upright table arranged forward of the drawing-rollers and over which the paper passes after leaving the rollers, a revolute brush in
- 30 front of the table, for applying paste to the back of the paper, a traveling apron upon which the paper passes after passing over the table to move the trimmed and pasted paper forward, and means, substantially as de-
- 35 scribed, for matching the paper while it travels forward on the apron, as set forth.
- 40 6. A machine of the class described, comprising a pair of drawing-rollers for the paper to pass between, circular knives or cutters for trimming the paper at one side thereof, an upright table over which the paper passes after leaving the rollers, a revolute brush in front of the table, for applying paste to the back of the paper, a receptacle for paste, a
- 45 roller in said receptacle for supplying paste to the brush and means, substantially as described, for adjusting said table relatively to the brush, as set forth.
- 50 7. A machine of the class described, comprising a pair of drawing-rollers for the paper to pass between, circular knives or cutters for trimming the paper at one side thereof, a table over which the paper passes after leaving the rollers, and a revolute brush in front of the table for applying paste to the back of the paper, said table being made in sections transversely adjustable relatively to one another, to render the width of the table somewhat less than the width of the paper under treatment, as set forth.
- 55 8. A machine of the class described, comprising a rack for supporting a roll of paper, said rack being held transversely adjustable, a guide-roll under which the paper passes after it unwinds from its rollers, a second guide-roll over which the paper passes, a pair of drawing-rollers between which passes the paper from the last guide-roll, and a revolute disk for engaging the paper on the top of the last-mentioned guide-roll, as set forth.
- 60 9. A machine of the class described, comprising a rack for supporting a roll of paper, said rack being held transversely adjustable, guide-rolls for the paper after it unwinds from its roller, a pair of drawing-rollers between which passes the paper from the last guide-roller, a revolute cutting-disk for engaging the paper on the top of the last-mentioned guide-roll, and means, substantially as described, for laterally adjusting said rack, as set forth.
- 65 10. A machine of the class described, comprising a rack for supporting a roll of paper, a transversely-extending guideway in which said rack is mounted to slide, drawing-rollers for the paper, cutters for trimming the paper, and means for adjusting the rack transversely to bring the selvage edge of the paper in proper relation to the cutters, as set forth.
- 70 11. A machine of the class described, comprising a pair of drawing-rollers for the paper to pass between, circular knives or cutters for trimming the paper, an upright table over which the paper passes after leaving the rollers, a rod on which the table is hung, a revolute brush in front of the table for applying paste to the back of the paper, and means for adjusting the table relatively to the brush, as set forth.
- 75 12. In a machine of the class described a table over which the paper passes, and means for applying paste to the paper, the said table being made in sections, rods engaging the ends of the sections, and means for adjusting the sections, for the purpose set forth.
- 80 13. A machine of the class described, comprising a rack for supporting a roll of paper, a pair of drawing-rollers for the paper to pass between, knives or cutters for trimming the paper, an upright table arranged forward of

the drawing-rollers and over which the paper passes after leaving the rollers, a revolvable brush in front of the table for applying paste to the back of the paper, means for adjusting the table relatively to the brush, a traveling apron upon which the paper passes after passing over the table, and means for matching the paper, as set forth.

In testimony whereof I have signed my name to this specification in the presence of 10 two subscribing witnesses.
